CUT STONE FOR COSTUME JEWELRY

William Wachtenheim, Great Neck, N. Y.

Application January 24, 1958, Serial No. 49,385

Term of patent 7 years

(Cl. D45—1)

Fig. 1 is a top plan view of a cut stone for costume jewelry, showing my new design;

Fig. 2 is a bottom plan view;

Fig. 3 is a side elevational view;

Fig. 4 is a front elevational view of the same;

Fig. 5 is a longitudinal sectional view taken on the line 5—5 of Fig. 1; and

Fig. 6 is a transverse sectional view taken on the line 6—6 of Fig. 1.

I claim:

The ornamental design for a cut stone for costume jewelry, substantially as shown.
